UNITED STATES PATENT OFFICE.

KARL MOHR, OF BEDFORD, INDIANA, ASSIGNOR TO LILLIE M. OWEN, OF BEDFORD, INDIANA.

RAILWAY-TIE.

1,165,274.

Specification of Letters Patent.

Patented Dec. 21, 1915.

Application filed August 31, 1915. Serial No. 48,323.

To all whom it may concern:

Be it known that I, KARL MOHR, a citizen of the United States, residing at Bedford, in the county of Lawrence and State of Indiana, have invented certain new and useful Improvements in Railway-Ties; and I do hereby declare the following to be a full, clear, and exact description of the invention, such as will enable others skilled in the art to which it appertains to make and use the same.

My invention relates to improvements in metallic railway ties and has for its primary object to generally improve and simplify the construction and operation of such devices so as to render them more practical, reliable and efficient in operation, durable and inexpensive to manufacture.

Another object is to provide a novel means for supporting and securing the rails upon the tie which acts to reinforce the tie as well as to hold the rail thereupon.

The above and additional objects are accomplished by such means as are illustrated in the accompanying drawings, described in the following specification and then more particularly pointed out in the claims.

With reference to the drawings, wherein I have illustrated the preferred embodiment 30 of my invention as it is reduced to practice, and throughout the several views in which similar reference numerals designate corresponding parts, Figure 1 is a top plan view of the tie, Fig. 2 is a fragmentary side elevation showing one of the rails thereon, and in section, Fig. 3 is an enlarged detail top plan view of the body portion of which the tie is formed, Fig. 4 is a longitudinal fragmentary sectional view taken through the 40 tie, Fig. 5 is an end elevation, Fig. 6 is a detail plan view of a locking washer to be used in connection with my improved tie, and Fig. 7 is a detail top plan view illustrating the manner in which the inner ends 45 of the rail supporting members are connected.

Referring to the drawings by characters of reference, the numeral 1 designates as an 50 entirety a channel-shaped elongated body portion for my improved tie and at each end has its side walls 2 and 3 joined adjacent their upper edges by an integral plate 4, which plate 4 restricts the opening in the ends of the tie.

Mounted within each end of the tie 1 is 55 a rectangular resilient rail supporting block 5 that is preferably formed of wood but which may be formed of any other suitable material. Formed opposite one another upon the inner faces of the side walls 2 and 3 60 of the channel-shaped body portion 1 are vertical flanges 6. The inner ends of the blocks 5 engage the flanges 6 which terminate at a point flush or slightly spaced from the upper edge of the side wall and 65 are prevented from further inward movement.

Formed on opposite sides of each end of the tie are upstanding lugs 7. These lugs 7 are joined with one another by means of 70 the plate 4 and are approximately V-shaped in cross section. A retaining flange 8 is formed on the upper edge of each of the lugs 7 and extends inwardly over the body portion of the tie so as to act as retaining 75 members in the manner which will be more fully described.

On opposite sides of the body portion on the side walls 2 and 3 at points spaced inwardly from the ends of the tie are formed 80 retaining members 9 and 10 respectively that consist of upstanding lugs with flanges on the upper edges thereof which are similar to the lugs 7 and the flanges 8 thereon.

The plate 13 is provided on opposite sides 85 and at points suitably spaced from one another with rail base engaging lugs or rail clamping members 14 that are designed to engage the base of a rail and hold the rail in position. The plate 13 is of such dimensions as to fit snugly upon the resilient supporting block 5. The retaining members 9 and 10 and flanges 8 and lugs 7 act to retain the plate 13 in position, said flanges 8 engaging upon the upper face of the plate. 90 A spike or other suitable fastening element 15 is driven through an aperture in the outer end of the plate 13 and into the resilient supporting block 5 so as to hold said block 5 in position. Formed integral with each 100 of the plates 13 on the inner edge thereof and at a point intermediate the end edges of said inner edge is an inwardly extending rod or arm 16 which is provided with a recess 17 upon one face thereof at its free 105 end. The recess which is formed in the arm or rod 16 is spaced slightly from the free ends thereof so that the end portions of

the rod extend into the recesses of each other and provide a tight joint as clearly shown in Fig. 1 of the drawing. These rods 16 are disposed centrally, that is in line with the longitudinal center of the body portion of the tie and since very little footing is provided track walking is prevented by the use of the skeleton construction provided by the body portion and arm 16. 10 Suitable fastening elements 18 are inserted through the overlapped ends of the arms 16 and nuts 19 are turned on the threaded end of said fastening elements. Mounted upon each nut 19 is a washer of the locking type 15 designated by 20 as an entirety which comprises a rectangular body portion having formed thereon bendable tongues 21. The body portion 20 is provided with a central aperture to receive the bolt or fastening element 18 and the bendable tongues 21 are designed to be bent to engage the sides of the nut.

In assembling my improved tie, the rail supporting members 11 and 12 are placed 25 upon the resilient supporting blocks 5 and are arranged in an angular position with relation to the tie at opposite sides thereof so that the rail engaging or clamping members 14 are spaced sufficiently to enable a rail to 30 be placed upon the plates 13, that is to say, the plates 13 are disposed approximately at right angles to their assembled position to arrange the member 14 slightly beyond the rails so that the latter may be placed on the 35 said plates 13. After the rails have been placed as described upon the plates 13, the arms 16 are drawn toward one another so that they overlap and the bolts or fastening elements 18 are then inserted through 40 the overlapped portions thereof. The arrangement of the retaining members 9 and 10 enables the plate to be drawn inwardly from opposite sides of the tie.

It will be observed that the resilient rail 45 supporting blocks provide the required track resiliency and thus it will be seen that the improved tie possesses all the resiliency of a wooden tie but is much more efficient and more durable by reason of its metallic construction.

In practice, I have found that the form of my invention, illustrated in the drawings and referred to in the above description, as the preferred embodiment, is the most efficient and practical; yet realizing that the 55 conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

What is claimed is:

1. A rail tie consisting of a channel-shaped metallic body portion, resilient rail supporting blocks mounted in the ends of said body portion, metallic rail supporting plates mounted upon said resilient rail supporting blocks, means to clamp the rails 70 mounted upon said plates, means to hold said plates upon said blocks, arms formed integral with said plates and extending inwardly toward one another and means to connect said arms with one another. 75

2. A metallic rail tie consisting of a channel-shaped metallic body portion, resilient rail supporting blocks mounted within said body portion at the ends thereof, metallic rail supporting plates mounted upon said blocks, means to hold said blocks in position, means to hold said plates upon said blocks, and arms formed integral with the inner ends of said plates and being detachably connected with one another at a point adjacent the center of the tie. 80

3. A metallic rail tie comprising a metallic body portion, resilient rail supporting blocks mounted upon the body portion, metallic rail supporting plates mounted upon the blocks, means to hold the plates upon the blocks, arms formed integral with the inner ends of said plates, extending inwardly and overlapping each other at their ends and means to secure said arms to one another inserted through the overlapped ends thereof. 90

4. A rail tie comprising a metallic body portion, resilient rail supporting blocks mounted upon the body portion, metallic rail supporting plates mounted upon the blocks, means to hold the plates upon the blocks, arms formed integral with the inner ends of said plates, extending inwardly and overlapping each other at their ends and means to detachably secure the overlapped ends of the arms to one another. 100

5. A metallic rail tie consisting of a channel-shaped body portion, resilient rail supporting blocks mounted within the body portion at the ends thereof, rail supporting plates mounted upon the blocks, retaining members carried by the tie, engaging and holding said rail supporting plates upon said tie, rail clamping members carried by said plates, fastening elements inserted through said plate and into said blocks and arms formed integral with said plates and being connected with one another. 110

In testimony whereof I affix my signature 120 in presence of two witnesses.

KARL MOHR.
